(57) CLAIM

The ornamental design for a compact travel nursing pillow, substantially as shown and described.

DESCRIPTION

FIG. 1 is a perspective view of a compact travel nursing pillow showing my new, original, and ornamental design;

FIG. 2 is a top view thereof;

FIG. 3 is a bottom view thereof;

FIG. 4 is a front-side view thereof;

FIG. 5 is a rear-side view thereof;

FIG. 6 is a left-side view thereof; and,

FIG. 7 is a right-side view thereof.

The broken lines in FIGS. 1-3, 6, and 7 depict a symbolic break that forms environment and portions of the article that form no part of the claimed design. The broken lines and the area between the break lines forms no part of the claimed design.
